UNITED STATES PATENT OFFICE.

JOHN SLATER, OF STOKE-UPON-TRENT, ENGLAND, ASSIGNOR TO WILLIAM S. PITCAIRN, OF NEW YORK, N. Y.

DESIGN FOR A JUG OR SIMILAR ARTICLE.

No. 38,627.

Specification for Design.

Patented June 18, 1907.

Application filed October 17, 1906. Serial No. 339,420. Term of patent 3½ years.

To all whom it may concern:

Be it known that I, JOHN SLATER, a subject of the King of Great Britain, residing at Brown Edge, Stoke-upon-Trent, England, have invented a certain new, original, and ornamental Design for Jugs or Similar Articles, of which the following is a specification.

In the accompanying drawing, the figure is an elevation showing the design for the jug.

I claim:

The ornamental design for a jug or similar article, as shown.

JOHN SLATER.

Witnesses:

JOHN W. LATIMER,
JESSE VARIS.
